COMBINED CUTTER TOOTH AND ADAPTER THEREFOR FOR EXCAVATING, DIGGING OR BUCKET LOADING

Sten Johan Dahlberg, Karlskoga, and Jouko Kalevi Korpi,
Degerfors, Sweden, assignors to AB Bofors, Bofors,
Sweden

Filed Feb. 26, 1974, Ser. No. 446,031

Claims priority, application Sweden Sept. 4, 1973

Term of patent 14 years

Int. Cl. D15—03, 04

U.S. Cl. D39—1 R

FIG. 1

FIG. 2

FIG. 3

FIG. 5

FIG. 6

FIG. 1 is a perspective view of a combined cutter tooth and adapter therefor for excavating, digging or bucket loading showing our new design;

FIG. 2 is a left end elevation thereof;

FIG. 3 is a right end elevation thereof;

FIG. 4 is a rear elevation thereof;

FIG. 5 is a top plan view thereof; and

FIG. 6 is a bottom plan view thereof.

We claim:

The ornamental design for a combined cutter tooth and adapter therefor for excavating, digging or bucket loading, as shown.
